UNITED STATES PATENT OFFICE

JEROME B. STERN AND BERNARD S. FRANKLIN, OF NEW YORK, N. Y.

LIGHTER

Application filed January 25, 1929. Serial No. 334,877.

This invention relates to lighters, and more particularly to a method and means for fueling flint-spark lighters.

A popular type of pocket and table lighter, for smokers, is a lighter having a fuel reservoir, preferably containing absorbent material for holding benzine, gasoline, alcohol, or other volatile fuel, a wick projecting out of the reservoir, and a flint-sparking mechanism for igniting the wick. Such a lighter is refueled by inverting it, removing a screw plug from its bottom, and transferring a quantity of fuel through the resulting opening by means of a medicine dropper or similar device. To lessen this difficulty special cans of fuel have been marketed, designed somewhat like an oil can, but these add greatly to the expense of the fuel, and are not nearly so commonly available as are the more usual fuels.

The primary object of our invention is to facilitate the fueling of such lighters, that is, to provide a self filling lighter, which we do by arranging the lighter to suck fuel upwards from an open body of the fuel preferably by varying the effective internal volume of the lighter.

A further object of our invention is to provide means for varying the effective internal volume of the lighter to obtain the desired pumping action, and to this end we provide an elastic sac which is in communication with the fuel reservoir of the lighter, and means to compress or release the sac in order to obtain the desired suction. The sac is normally left released, making the volume of the lighter a maximum, and thereby holding the charge of fuel.

A further object of our invention is to provide a pumping arrangement permitting successive charges of fuel to be drawn into the lighter, if needed, without necessitating suction and discharge valves, such as are employed in an ordinary pump. To do this we take advantage of the fact that these lighters ordinarily do not contain free liquid fuel, but are arranged with absorbent fuel holding material which is merely saturated with the fuel, to practice the following method; we connect the lighter with an open body

of the fuel, and thereafter increase the effective internal volume of the lighter in order to suck fuel into contact with the absorbent material, repeating this operation until the absorbent material is fully saturated, and, if desired, finally reducing the internal volume to discharge any excess fuel. The absorptive property of the absorbent fuel holding material is utilized to replace suction and discharge valves. Of course, the displacement may be so designed that a single charge of fuel will ordinarily serve to saturate the absorbent material, but it is convenient to be able to repeat the operation, if necessary to obtain full saturation.

To connect the lighter with the body of fuel it is desirable to have a suction pipe reaching toward the fuel, but this pipe, obviously, should not project out of the lighter except during refueling. To provide such a suction pipe is another object of our invention, which we fulfill with a suction pipe pivoted to the lighter, and provided with resilient means for causing said pipe to position itself either substantially parallel to the lighter, or substantially perpendicular thereto, and, to prevent fuel evaporation, additional means for closing an end of the pipe when it is in the parallel position.

To prevent fuel from entering the elastic sac is a further object of our invention, which we fulfill by so spacing the points of connection of the sac and of the suction pipe with the reservoir that fuel does not rise in the reservoir to a level sufficiently high to enter the sac.

Our invention is further described in the following specification, which is accompanied by drawings in which Figure 1 is a partially cross sectioned elevation of a simple form of our invention; Figure 2 is a bottom view of the arrangement shown in Figure 1; Figure 3 is a cross section of a modification employing a lever actuated filling system; Figure 4 is an elevation of the modification shown in Figure 3 improved by a combined wick cap arm and suction pipe; Figure 5 is a plan view of Figure 4; and Figure 6 is a detail view.

Referring to Figure 1 it will be seen that

there is a lighter of conventional form, comprising a body 2, which acts also as a fuel reservoir, a wick 4, a wick cap 6 supported on a pivoted wick cap arm 8, flint-supporting mechanism 10, and flint abrading mechanism none of which is visible except the knurled thumb wheel 12.

In the present lighter, however, the sides of the body 2 extend below the bottom of the reservoir 14 and filling cap 16, to form a compartment beneath the reservoir, made accessible by a hinged door 18. Within the compartment thus formed there is located a suction pipe 20 and an elastic sac or bulb 22. The suction pipe 20 is pivoted to the bottom of the lighter through an elbow 24, threaded to a square member 26, which is also engaged by a resilient spring 28, forcing the suction pipe to remain either substantially parallel to the lighter, as shown, or substantially perpendicular thereto, when used for filling. In the parallel position the end of the suction pipe 20 is closed against a tapered seat 30 in order to prevent evaporation of the fuel held in suspension by the absorbent fuel holding material 32. The elastic sac 22 is connected to a tube 34, which rises within the fuel reservoir to a considerable height in order to prevent fuel from entering the sac itself during the filling operation.

To refuel the lighter the door 18 is opened, the suction pipe 20 is snapped into its vertical position, the sac 22 is moved out of the way to the dotted position indicated in Figure 1, the suction pipe 20 is immersed in a body of fuel, the sac 22 is squeezed either before or after the immersion and is released after the immersion, sucking fuel into the fuel reservoir and into contact with the absorbent material 32, which takes it up.

Figure 2 is a bottom view of Figure 1, and shows how the suction pipe 20 is fitted to the member 26, which is internally threaded to engage with a thread on the pipe elbow 24. In this manner a flow connection is established from the suction pipe into the fuel reservoir, and, at the same time, the suction pipe may turn about the thread the necessary quarter turn. The member 26 is made square for cooperation with the spring 28, which either presses the suction pipe 20 against the seat 30, or holds it in a perpendicular position for filling.

Attention is now directed to Figure 3, which is an improvement over the arrangement shown in Figure 2 in that the elastic sac 40 is permanently protected by a portion of the body of the lighter, separated from the fuel reservoir by a partition 42. The sac 40 is fixed to a removable threaded member 44, a hole in which aligns with a hole 46 in the partition 42, thereby placing the sac in communication with the fuel reservoir. The point of communication is set at the top of

the lighter because the suction pipe is attached at the bottom, the resulting spacing serving, like the tube 34 in Figure 1, to prevent fuel from entering directly into the sac itself. Upon actuation of a filling lever 50, pivoted to the lighter body at 52, the sac 40 is compressed by a plate 48, pivoted to the inner end of the lever.

As before, the lighter is provided with a suction pipe 20, oscillating on an elbow 24, and closing against a seat 30 in response to a spring 28. In this case the room taken by the suction pipe 20 is relatively small, and, there being no free sac, the door for closing the bottom of the lighter may be dispensed with.

In a copending application of Albert M. Franklin, Serial Number 334,880, filed concurrently herewith, it is suggested that the separate suction pipe be dispensed with by utilizing the wick cap arm as a suction pipe. An arrangement embodying this improvement is indicated in Figure 4, in which the usual wick cap 6 is in flow communication with a tubular wick cap arm 60, which in turn is connected to a square member 62 engaging a spring 64, and threaded to an elbow 66, which is connected to the fuel reservoir. The closing of the wick cap against its seat closes the end of the pipe 60 to prevent free evaporation. Sac 40 and screw member 44 are in this case inverted, so that the sac is again in communication with the fuel reservoir at a point remote from the point of connection of the suction pipe 60, thus preventing fuel from entering the sac itself. The screw member 44, being at the bottom of the lighter, does not mar its appearance, and, as before, the entire sac may be removed for repair by unscrewing the member 44.

Figure 5 is a plan view of the arrangement shown in Figure 4, and illustrates how the wick cap 6 is connected to a suction pipe 60, mounted on a square member 62, which in turn is threaded to a pipe elbow 66 and engages a positioning spring 64. The flint-sparking mechanism 10, which may be of conventional type, has been cut away in order to better show the suction pipe connection.

Figure 6 is a detail of the suction pipe connection, and shows how the square member 62 is threaded to engage the pipe elbow 66, while the suction pipe 60 is set into the square member 62.

Any pivoted connection which simultaneously permits of flow, either always, or else only in the vertical position of the suction pipe, may equally well be used. We have elected to show the form illustrated merely because of its extreme simplicity.

In all cases the customary manual filling plug 16 is provided, through the opening for which the wick and absorbent material are put into the reservoir, and in which spare flints may be kept.

If the lighter has become completely dried

- out the fuel charge needed to saturate the lighter may exceed the displacement of the sac. We recognize that it is quite feasible to use the sac merely as a pump displacement mechanism, and to additionally provide suction and air discharge valves at the bottom and top of the reservoir, respectively, to enable one to repeatedly pump fuel therein. However, we consider the much simpler illustrated arrangement to be preferably because with the usual lighter construction it is anyway desirable that there be no free liquid in the fuel reservoir which might leak out of the wick tip, filling plug, or suction pipe, and soil the hands and clothing of the user. Fuel in excess of saturation being undesirable the absorptive property of the fuel holding material may itself be taken advantage of to act as a form of suction and discharge valve, for fuel brought into contact with the absorbent material will be held, and if insufficient, the filling operation may be repeated until full saturation is obtained. The sac may be finally squeezed to discharge any excess liquid, thereby insuring that the absorbent material, while fully saturated, is not immersed in free liquid.
- We claim:
1. The combination with a lighter having a fuel reservoir, of suction means to suck fuel upwards into the reservoir, and means to prevent the fuel from entering the suction means. 80
  2. The combination with a lighter having a fuel reservoir, of an auxiliary chamber of variable volume in communication with the reservoir in order to vary the effective internal volume thereof in order to suck fuel therein, and means to prevent the fuel from entering the auxiliary chamber. 85
  3. A self filling lighter comprising a fuel reservoir, a suction pipe for connecting the reservoir with an open body of the fuel, an auxiliary chamber of variable volume also in communication with the reservoir, and means to vary the volume of the auxiliary chamber in order to suck fuel through the pipe into the reservoir. 90
  4. A self filling lighter comprising a fuel reservoir, a suction pipe for connecting the reservoir with an open body of the fuel, an elastic sac also in communication with the reservoir, and means to compress or release the sac in order to suck fuel through the pipe into the reservoir. 95
  5. A self filling lighter comprising a fuel reservoir, a suction pipe for connecting the reservoir with an open body of the fuel, an elastic sac also in communication with the reservoir, and means to compress or release the sac in order to suck fuel through the pipe into the reservoir, the points of connection of the sac and of the pipe with the reservoir being so spaced that fuel does not enter the sac. 100
  6. A self filling lighter comprising a fuel reservoir containing absorbent fuel holding material, a suction pipe for connecting the reservoir with an open body of the fuel, an elastic sac also in communication with the reservoir, and means to compress or release the sac in order to suck fuel through the pipe into contact with the absorbent material to saturate it, the points of connection of the sac and of the pipe with the reservoir being so spaced that fuel does not enter the sac. 105
